UNITED FOLDING LEG TABLE

William Vangor, Bridgeport, Conn., assignor to Lorraine Novelty Manufacturing Co., Inc., Bridgeport, Conn., a corporation of Connecticut

Application July 6, 1954, Serial No. 441,381

17 Claims. (Cl. 311—82)

This invention relates to tables having folding legs, such as card tables, which permits the easy storing of the table when it is out of use.

Heretofore, to hold the legs in extended position braces or supports such as toggle and link members have been connected to the legs and to the table frame so as to extend substantially below the marginal portions of the table frame. When the legs are in extended position, the supports are in full view and detract from the appearance of the table and occupy the corner space between the marginal frame and the leg, and thus limit the leg space available to persons sitting at the table.

An object of the present invention is to provide a mechanism and leg hardware for supporting the legs in their extended position, which is so constructed that it will be entirely hidden from view in the normal position of use of the table.

Another object of this invention is to provide improved operating connections for effecting the conjoint positioning of all of the legs of the table through manual operation of one of the legs.

A feature of the present invention is the provision of means for locking the legs in extended position, which means includes a self-acting member individual to each leg which not only locks the leg against folding against the marginal frame of the table but also takes up any lost motion or looseness that may be necessarily present to permit easy operation of the device, combined with means for manually releasing all of said individual locking means when any one of them is released to allow all the legs to be moved to folded position.

A further feature of this invention is the provision of means for simultaneously moving all of the legs to and from extended position, which means is independent of the locking and unlocking means and operates independently thereof.

Other features and advantages will hereinafter appear.

In the drawings:

Figure 1 is a bottom plan view of a table made according to the present invention with the legs in collapsed, non-use position.

Fig. 2 is an enlarged fragmentary bottom plan view of one corner of the table showing the leg folded against the table top.

Fig. 3 is an enlarged fragmentary cross sectional view of an elevation of one corner of the table with the leg in folded position.

Fig. 4 is a view similar to that of Fig. 3 but with the leg in extended position.

Fig. 5 is an enlarged view of the locking means in operative position looking in the direction of the arrow A of Fig. 4.

Fig. 6 is an enlarged view of another form of a handle for actuating the leg-releasing means.

Referring to Figs. 1—5, the present invention is applied to a card table of the type wherein the legs fold automatically within the marginal frame 11 of the table top

2

12. Each leg 10 is secured to a metal plate 13 which is shaped to partially encompass the top of the leg and has a pair of parallel flanges 14 extending beyond the legs, the portion extending beyond the legs having openings 15 to receive hinge pins 16 to attach it to upstanding hinge ears 17a provided on a bracket 17. The bracket 17 fits in the corner formed by the adjoining sides 11a of the marginal frame 11 and is secured thereto by screws 17b. The bracket serves as a brace as well as a hinge part and mounting plate for the leg-folding mechanism.

According to the present invention, each leg 10 has an improved individual locking mechanism located at each table corner for positively locking the leg in its extended use position. One of such mechanisms will now be described in detail, it being understood that the other locking mechanisms are similar in every respect.

As shown in Figs. 2, 3, 4 and 5, the bracket 17 has a vertical flange 18 to which is attached a cam lever 19. The cam lever, as shown in Fig. 5, is shaped to provide a substantially straight line camming surface 20 and a curved camming surface 21, and a lug 22 projecting from the latter. The lever 19 is mounted for movement about the pivot pin 17c and is urged into operative position by means of a spring 23 which is connected to the lever and is shaped to form a loop at its other end bearing against a cut-out seat provided in the vertical flange 18 of the bracket.

The portion of the leg-carrying plate 13 facing the cam lever 19 when the leg is moved to extended position is provided with a pin 24 which is so located that as the leg approaches its extended position the pin 24 engages the camming surface 20 and moves the cam lever 19 about its pivot against the action of the spring 23 until the pin 24 is at the intersection of the camming surfaces 20 and 21, at which time the spring is again free to yieldably urge the camming surface 21 against the pin 24 to move the latter and the leg to which it is attached as far as the leg may travel. The cam surface 21 is so "flat" that when engaged with the pin 24 it acts as a barrier or lock against any movement of the leg away from extended position.

In order to assure that the leg is perpendicular with the table, the plate 13 is provided with stop members 25 which engage the bracket when the leg is in completely extended position. With the lock of the present invention, the stops 25 will always be in firm contact with the bracket and the possibility of a wobbly leg is entirely eliminated because the spring acting on the cam lever 19 will constantly tend to cause the curved cam 21 to move the pin 24 and the leg should any movement of the leg occur until the stops 25 are in firm engagement with the bracket.

It will thus be seen that each leg is individually locked in extended position against any perceptible movement by a locking device which automatically completes the movement of the leg to its ultimate perpendicular position once the leg becomes proximate its extended position. This is not possible with toggle braces which as a practical matter to lock must be moved beyond dead center, loose motion being unavoidably present. It is also not possible by the mere locking of the leg-moving mechanism since in such case considerable lost motion is present. The legs cannot be rigidly held if there be such lost motion either between the leg and the locking mechanism or the leg and the lock-actuating mechanism.

In order to release the leg the cam lever 19 and pin 24 must be disengaged from each other. To do this, the present invention provides means for engaging the cam lever and moving it against the tension of the spring 23 clear of the leg pin 24. As shown, a releasing lever 26 is secured to the horizontal flange 27 of the bracket 17

about a pivot 28 which is at right angles to the pivot 17c for the cam lever. The lever 26 has an arm 29 provided with a finger 30 to engage the lug 22 on the cam lever 19. When the lever 26 is operated it engages the lug 22 and swings the cam lever entirely clear of the pin 24 so that the leg is then free to be folded against the table top. The lever 26 is mounted for movement about the pivot 28 in the space between the upper end of the leg and the bracket 17, so that the finger moves in the path of movement of the lug 22 of the cam 19.

In order to release the leg from its locked extended position as shown in Figs. 4 and 5, the lever 26 is provided with a handle 31 so that it may be manually rotated about its pivot. The handle 31 is located adjacent the marginal frame 11a so that by placing the thumb and fingers, the one on the frame and the other on the handle and squeezing, the handle may be easily operated to release the leg. Upon release of the cam lever after movement of the leg to take the pin 24 out of range thereof, the action of the spring on the cam lever 19 returns it to starting, i. e., ready-to-lock, position, at the same time rotating the lever 26 about its pivot by engagement of the lug 22 with the finger 30, until a flange 32 on the lever 26 engages a stop to limit its movement. As shown, the stop is the upstanding hinge ear 17a of the bracket 17. If desired, a limiting flange 33 may be provided on the bracket which is so located thereon that when the arm 29 on the lever 26 is in contact therewith the curved camming surface 21 will be outside of the path of movement of the lug 24.

As shown in Fig. 5, the vertical flange 18 may have a clearance opening 34 for the end of the pin 24.

The leg mounting and locking mechanism, as described so far, is complete and operative of itself and a table provided with such mechanism is entirely serviceable, but it would require that each leg be separately released by a manual operation and separately moved by a manual operation between folded and extended positions, not to mention the manipulation of the table to make these repetitive operations reasonable convenient.

Heretofore, in folding tables of the type herein involved, it was proposed to provide means for simultaneously, that is of say in one operation, moving the legs and unlocking or locking the legs of the table so as to avoid the necessity of individual leg operation and its inconvenience. However, while such proposals have been acceptable and satisfactory for the most part, they have the disadvantage that if the locking means for one of the legs failed to effectively lock its leg against movement, casual or inadvertent movement of that leg, as for instance by a person striking his foot or knee against it, would unlock all the legs and the table would completely collapse with disastrous consequences, especially when the table is supporting liquid refreshments.

To avoid this possibility, the present invention not only provides an individual lock for each leg, but provides one set of means interconnecting the mechanism associated with the legs for solely unlocking the legs and another set of means for solely causing the legs to be moved to and from extended position simultaneously—provision being made for sufficient lost motion in the operation of the leg-operating means to permit the individual leg-locking means to perform their functions.

In order to facilitate the unlocking of all of the legs simultaneously, the release levers 26 are, according to the present invention, provided with interconnecting means, and as shown in Fig. 1, there are interconnecting link members 35, each connected at one end to an adjacent arm 29 and at the other end to an arm 29a on the remote release lever 26, each of which thus functions as a bell crank having arms 29 and 29a. Thus, each release lever moves in unison with the others due to the manual operation of one and each moves its associate cam lever to remove the camming surfaces 21 clear of the path of movement of each leg and permits the folding of the leg.

In the form of the invention illustrated where the re-

leasing levers 26 are interconnected for coordinate movement, each of the releasing levers is provided with a handle 31. Hence, when the table is supported on its edge, which is its usual position when the legs are being unfolded, there will always be one releasing handle at the upper edge of the table. However, should it be desired operating handles on diagonally opposite releasing levers 26 may be omitted, since even then there would always be at least one handle at or near the upper edge of the table for manipulation by the user. Moreover, when the releasing levers are interconnected as shown, all of the releasing handles 31 may be omitted, and in such case the releasing levers may be operated by direct manipulation of any of the interconnecting links 35—for instance, by providing on the interconnecting link 35 a handle or extension 35a.

According to the present invention, improved mechanism for effecting conjoint movement of all the legs to and from extended position, comprises pairs of engaging tooth members such as gears operatively connected for coordinate movement so that movement of one of the legs simultaneously moves all of the legs.

As shown, an operating segmental gear 36 is pivotally secured to the horizontal flange 27 of the bracket 17 and is mounted for rotation on the pivot 28 on which the release lever 26 is mounted. The operating gear 36 meshes with an operated gear segment 37 which as shown is pivotally secured to an upstanding flange 38 of the bracket 17, and between the flange and the marginal frame 11a, the bracket having an offset portion 42 to accommodate the gear 37. The operated gear segment 37 has an extension 39 having a pin-and-slot connection with the adjacent leg. As shown the slot 44 is provided in the arm 39 of the gear segment and a pin 41 on the leg slides 35 in the slot.

The operating gears 36 are interconnected by means of links 42, each of which is connected at one end to a pivot pin 43 on an adjacent gear 36 and at the other end on a pivot 44 on a remote gear 36, the gear segments thus functioning as bell cranks for transmitting motion around the corners from one gear to the next causing all of the legs to be operated when any one leg is manually moved. For convenience, the gear segment 36 has been designated as the operating gear and the gear 37 as the operated gear. It will be understood, of course, that the gear 36, which is on the leg being manually moved, becomes on that occasion an operating gear and the gear 37 which it engages becomes an operated gear, all the other gears 36 operating the gears 37 which are connected by pin-and-slot connections to the legs.

In operation, there is necessarily some clearance or lost motion between the gear 36 and the gear 37 standing at right angles to it, and also between other parts including the pivot pins and interconnecting links. This lost motion is taken advantage of by the present invention since, by reason of it, the automatic camming action of the locking lever 19 may function to complete the movement of its associated leg regardless of the interconnections between the legs.

From the foregoing description it can be seen that with the leg-attaching means as constructed according to the present invention, none of the operating mechanism extends or projects below the marginal frame of the table, and the table in its in-use position makes a more slight appearance than those folding tables which utilize mechanism extending below the marginal portion.

Variations and modifications may be made within the scope of the claims and portions of the improvements may be used without others.

I claim:

1. In a folding table the combination with a top, a top frame and legs movable to extended and retracted positions; a mounting for each leg including a hinge connection between the top and the leg; means locking each leg in extended position against movement comprising

cooperating members, one on the leg and one on the frame, one of said members being a pin and the other a wedging-type cam located relatively to be normally disengaged but to be brought into cooperation when the leg approaches extended position; and resilient means for pressing said cam and pin into wedging engagement to force completion of the movement of the leg to the limit of its extended position and lock the leg in such position.

2. In a folding table the combination with a top, a top frame and legs movable to extended and retracted positions; a mounting for each leg including a hinge connection between the top and the leg; means locking each leg in extended position against movement comprising cooperating members, one on the leg and one on the frame, one of said members being a pin and the other a wedging-type cam located relatively to be normally disengaged but to be brought into cooperation when the leg approaches extended position; resilient means for pressing said cam and pin into wedging engagement to force completion of the movement of the leg to the limit of its extended position and lock the leg in such position; and means interconnecting the locking means of the several legs for simultaneous operation to release each locking means to free the legs for movement away from extended position.

3. In a folding table the combination with a top, a top frame and legs movable to extended and retracted positions; a mounting for each leg including a hinge connection between the top and the leg; locking means individual to each leg for forcing completion of movement of the leg to completely extended position and locking the leg in such position; means interconnecting the locking of the several legs for simultaneous operation to release each locking means to free the legs for movement away from extended position; means interconnecting the legs for simultaneous movement of all the legs when one leg is moved, said leg-interconnecting means including lost motion whereby each leg-locking means is free to operate on its leg regardless of the positions of the other legs.

4. In a folding table the combination with a top, a top frame and legs movable to extended and retracted positions; of a mounting for each leg including a hinge connection between the top and the leg; locking means for each leg including a pivoted cam mounted on said table frame for movement about a horizontal pivot and a lug on the leg positioned to coat with said cam when the leg is in extended position to prevent movement of the leg about the hinge connection; and means for urging the cam to leg-locking position.

5. In a folding table the combination with a top, a top frame and legs movable to extended and retracted positions; of a mounting for each leg including a hinge connection between the top and the leg; locking means for each leg including a pivoted cam mounted on said table frame for movement about a horizontal pivot and a lug on the leg positioned to coat with said cam when the leg is in extended position to prevent movement of the leg about the hinge connection; means for urging the cam to leg-locking position; and manually operable means movable in the plane of the table top for releasing said locking means to permit the leg to be hingedly moved to retracted position.

6. In a folding table the combination with a top, a top frame and legs movable to extended and retracted positions; of a mounting for each leg including a hinge connection between the top and the leg; locking means for each leg including a pivoted cam mounted on said table frame and a lug on the leg positioned to coat with said cam when the leg is in extended position to prevent movement of the leg about the hinge connection; means to move said cam to inoperative position to unlock the leg; and manually operable means including means at

each leg position to simultaneously move all of said cam-moving means when one of the latter is moved by said manually operable means.

7. In a folding table the combination with a top, a top frame and legs movable to extended and retracted positions; of a mounting for each leg including a hinge connection between the top and the leg; locking means for each leg including a pivoted cam mounted on said table frame and a lug on the leg positioned to coat with said cam when the leg is in extended position to prevent movement of the leg about the hinge connection; means to move said cam to inoperative position to unlock the leg; and means including manually operable means including means at each leg position to simultaneously move all of said cam-moving means when one of the latter is moved by one of said manually operable means.

8. In a folding table the combination of a table top; a plurality of legs; means for hinging the legs on the table top for movement to and from extended position; means for interconnecting the legs for simultaneous movement of all by one; a cam on said table, one for each leg, operative when the leg is in extended position to lock the leg against movement thereof; means for each leg for releasing said cam; and means independent of the means for moving the legs for connecting said releasing means for simultaneous movement of all by one.

9. The invention as defined in claim 8, in which the leg-interconnecting means includes pairs of rotatable engaging toothed members operatively connected to each other and said legs.

10. The invention as defined in claim 8, in which the leg is provided with a pin to coat with said cam to lock the leg against movement.

11. The invention as defined in claim 1, in which the cam is mounted for movement in a plane perpendicular to the table top and in its locking position lies substantially normal to the path of movement of the pin on the leg to prevent movement of the leg about its hinge connection.

12. Leg hardware for a folding table including a bracket member for attachment to the corner of the table having a horizontal and vertical flange; means attachable to the leg for pivotally mounting the leg for movement about the horizontal flange including hinge means and a vertically disposed plate carrying a pin; a cam on said vertical flange; and a resilient means urging said cam into engagement with the pin to prevent movement of the leg-attaching means.

13. Leg hardware for a folding table including a bracket member for attachment to the corner of the table having a horizontal and vertical flange; means attachable to the leg for pivotally mounting the leg for movement about the horizontal flange including hinge means and a vertically disposed plate carrying a pin; a cam on said vertical flange; a resilient means urging said cam into engagement with the pin to prevent movement of the leg-attaching means; and a manually operable lever carried by the horizontal bracket for actuating said cam to unlock the leg-attaching means.

14. Leg hardware for a folding table including a bracket member for attachment to the corner of the table and having a horizontal and a vertical flange; leg-attaching means pivotally mounted on the horizontal flange including hinge means and a vertically disposed plate carrying a pin; a cam on said vertical flange having a straight-edge portion and an intersecting curved camming surface; and a resilient means urging said camming surfaces into the path of the pin to coat first with the straight-edge portion to retract the cam, then the curved surface to allow the latter to engage the pin and prevent movement of the leg-attaching means when the pin is in engagement with said curved camming surface.

15. Leg hardware for a folding table including a bracket member for attachment to the corner of the table and

having a horizontal and a vertical flange; leg-attaching means pivotally mounted on the horizontal flange including hinge means and a vertically disposed plate carrying a pin; a cam on said vertical flange having a straight-edge portion and an intersecting curved camming surface; a resilient means urging said camming surfaces into the path of the pin to coat first with the straight-edge portion to retract the cam, then the curved surface to allow the latter to engage the pin and prevent movement of the leg-attaching means when the pin is in engagement with said curved camming surface; and a manually operable lever carried by the horizontal bracket for actuating said cam to unlock the leg-attaching means.

16. In a folding table the combination of a table top; a plurality of legs; means including hinges for attaching the legs to the table top for movement to and from extended and retracted positions; means for conjointly moving all of said legs by one including pairs of interengaging rotatable toothed members associated with each of said legs, one of each of said pairs of toothed members connected to its associated leg for movement therewith; and means interconnecting each of the other of said pairs of toothed members whereby movement of one of said legs will simultaneously rotate all of said rotatable members and move all of the other legs conjointly. 25

17. In a folding table the combination of a table top; a plurality of legs; means including hinges for attaching the legs to the table top for movement to and from extended and retracted positions; means for conjointly moving all of said legs by one including pairs of interengaging rotatable toothed members associated with each of said legs, one of each of said pairs of toothed members rotatable about a horizontal pivot and connected to its associated leg for movement therewith, the other of said pairs of toothed members each being mounted for movement about a vertical axis; and means interconnecting each of said toothed members whereby movement of one of said legs will simultaneously rotate all of said rotatable members and move all of the other legs conjointly.
